BURNER CONTROL SYSTEM

William A. Ray, Glendale, Calif.

Application July 19, 1940, Serial No. 346,363

10 Claims. (Cl. 236—1)

This invention relates to a system for controlling the operation of a fluid fuel burner, such as a gas burner utilized to heat an oven in a range.

In the systems of this character, it has been proposed heretofore to provide an arrangement whereby the temperature of the oven or other space to be heated may be maintained by a presetting mechanism, such as a dial. These systems however are apt to be inaccurate; and it is not easy to provide highly important safeguards to ensure closing of the valve controlling the flow of fuel upon the burner failing to light or when the flame for any other reason is extinguished.

It is one of the objects of this invention to provide a system that is simple and reliable in operation, and that can maintain the temperature of the range within quite close limits.

It has been common to provide the gas cock controlling the oven burner on the front of the range, and often a thermostatic control unit is combined with this cock. This type of installation requires a considerable amount of piping for the gas up to the front of the range where the gas cock is located for accessibility. This piping introduces additional leak hazards at the pipe joints and at the cock. This is highly disadvantageous, because the pipe must often be brought to places where quite high temperatures exist. The gas cock also, is apt to stick or leak as a result of it being subjected to these temperatures. By the aid of this invention, the objectionable piping is obviated; and instead resort is had to electric wiring. The gas valve is conveniently located in a safe place, and remotely controlled by the aid of electrical energy.

These results are obtained by the aid of an automatically operated safety valve, arranged to have a low fire as well as a high fire position, and that may be operated to close completely upon failure of the pilot flame or when it is desired to discontinue the oven heat. Such a valve is described in a prior application, Serial No. 335,085, filed on May 14, 1940, in the name of William A. Ray, and entitled Fluid control valve. It is another object of this invention to make it possible to utilize a valve of this character in an effective and simple manner for the control of temperature in an oven.

This invention possesses many other advantages, and has other objects which may be made more easily apparent from a consideration of one embodiment of the invention. For this purpose there is shown a form in the drawing accom-

panying and forming part of the present specification. This form will now be described in detail, illustrating the general principles of the invention; but it is to be understood that this detailed description is not to be taken in a limiting sense, since the scope of this invention is best defined by the appended claims.

Referring to the drawing:

Figure 1 is a diagrammatic representation of 10 a system embodying the invention; and

Figs. 2 and 3 are diagrammatic sectional views of the valve structure utilized in the system, respectively showing low fire and high fire positions.

15 In the present instance there is shown a gas burner 1 adapted to be supplied with fuel through a conduit leading from a control valve structure 3. This valve structure 3 is described and claimed in the previously filed application Serial 20 No. 335,085 hereinbefore referred to. This valve structure is intended to have three positions. The closed position is illustrated in Fig. 1. A low fire position is shown in Fig. 2 and a high fire position is shown in Fig. 3. While the manner 25 in which these three positions may be obtained by a unitary valve or a number of valve structures is not important so far as the system is concerned, a short description of the valve structure illustrated may be included for the 30 sake of completeness.

The valve structure 3 may be provided with a valve body 4 having an inlet chamber 5 and an outlet chamber 6. Separating the two chambers is a wall or partition 7, through which extends 35 a port opening 8.

A valve closure structure is adapted to co-operate with the port 8. This valve closure structure may include a disk-like member 9 adapted to be seated on the tapered annular valve seat 40 10, surrounding port 8. In this way communication between the inlet chamber 5 and outlet chamber 6 is interrupted.

The closure structure is shown as carried by 45 a flexible diaphragm 11. The upper surface of the diaphragm is subjected in the position shown in Fig. 1 to the inlet pressure, whereby the closure 9 is urged to the closed position. For this purpose a casing 12 forming a chamber 13 is provided above the valve body 4. The diaphragm 11 50 forms a flexible wall of the chamber. Inlet pressure in the chamber 13 is provided by the conduit 14 leading from the inlet chamber 5 directly into the pressure chamber 13.

Provisions are made to reduce the pressure in chamber 13 by closing conduit 14 and by open-

ing chamber 13 to atmosphere. For example, this may be accomplished by the aid of an electromagnet 15 shown in this instance as located within the chamber 13. This electromagnet when energized operates to rotate a pivoted armature 16 against the force of a spring 17. The upper end of the armature when the electromagnet 15 is deenergized, serves to close the jet opening of a conduit 18. This conduit 18 would otherwise permit venting of the chamber 13 to atmosphere; for example through another chamber 19 and a vent 20, leading from that chamber.

The armature 16 when the electromagnet 15 is energized will be rotated in a clockwise direction to close the jet opening of the conduit 14. In this way passage of fluid under pressure of this chamber 13 is stopped. At the same time conduit 18 is opened and the fluid pressure in chamber 13 is reduced through passage of the fluid into chamber 19 and to atmosphere through vent 20.

The position assumed by the valve parts when the electromagnet 15 is energized is illustrated in Fig. 2. The pressure in the chamber 13 is reduced to a minimum, and therefore the valve closure 9 is moved upwardly by the inlet pressure in chamber 5 operating on the lower surface of diaphragm 11. For this position (corresponding to the low fire), the fuel in passing to the outlet chamber 6 is confined to a restricted passageway 21 formed in wall 7 and opening in the wall of port 8. This restriction is accomplished by the upward movement of a supplemental closure 22 joined to the main closure 9 by the intermediate rod 23. This supplemental closure 22 rises and seats against the tapered valve seat 24 formed around the bottom of the port 8. Accordingly fuel is not permitted to pass directly through the port 8. The fuel from inlet chamber 5 flows as indicated by the arrows, downwardly into the port 8 and thence through the restricted passage 21 in to the outlet chamber 6. Accordingly a restricted flow of fuel corresponding to low fire is permitted for this position of the valve.

In order to pass to high fire position, the closure structure 8-23-22, is moved to the position illustrated in Fig. 3; that is, both of the closure members 9 and 22 are open. Therefore fuel may pass from chamber 5 entirely through the port 8, past the closure 22 into the outlet chamber 6.

In order to obtain this intermediate position of the valve closure structure, the pressure in chamber 13 is raised above atmosphere but of such a value as not to cause the valve closure structure to assume the closed position of Fig. 1. This increase in pressure is obtained by energization of an electromagnet 25 located in the chamber 19. This electromagnet operates upon a pivoted armature 26. A spring 27 urges the armature 26 to the position shown in Figs. 1 and 2 when the electromagnet 25 is deenergized. In this unattracted position, the vent 20 is opened to atmosphere. However, when the electromagnet 25 is energized, the armature 26 assumes the position of Fig. 3. The vent 20 is now closed. At the same time, in spite of the closing of conduit 14, some fluid is permitted to pass into chamber 13. This is accomplished through the passageway 28 in wall 7 and opening in port 8; and through conduit 29 to chamber 19. This conduit 29 is closed by the armature 26 while the electromagnet 25 is deenergized, but is open

for the energized condition. From chamber 19 fluid pressure may flow through the conduit 18 into the chamber 13. Since the fuel encounters restricted passageways in passing from the port 8 through passageway 20, conduit 29, chamber 19 and conduit 18, the pressure in chamber 13 remains always somewhat less than in chamber 5, and accordingly the valve closure structure is not urged to the position of Fig. 1 but assumes the intermediate position of Fig. 3. In this intermediate position the closure 22 is freed from its seat 24 and the valve structure assumes the high fire position.

The control of the valve structure to render it completely inactive or fully closed as in Fig. 1 is effected by the control of the electromagnet 15. If the electromagnet 15 is deenergized as in Fig. 1, the valve structure 3 is surely closed, whether or not the electromagnet 25 be energized. Accordingly the electromagnet 15 is the dominant control for causing the valve to close completely. When the electromagnet 15 on the other hand is energized, the condition of energization of magnet 25 is determinative of the amount of fuel which passes to the outlet chamber 6 and burner 1. With the electromagnet 25 deenergized, the passage of fuel is restricted corresponding to the low fire position of Fig. 2. When the electromagnet 25 is energized as in Fig. 3, the valve structure is in high fire position.

Although a specific form of valve structure capable of assuming the three positions has been described, the principal features of the invention are not all dependent upon this valve structure

35 The electromagnets 15 and 25 are arranged in control circuits, as for example for controlling the temperature attained in an oven of a range. The temperature control may be effected for example by the aid of an extensible bellows 40 connected to a pressure cell 31. This pressure cell 31 may be located so that the vapor pressure therein is a function of the temperature to be controlled. Cell 31 usually encloses, for this purpose, a readily volatilizable liquid. 45 The pressure attained in the bellows structure 30 accordingly depends upon the temperature to which the cell 31 is subjected. The member 30 is shown as operating a contact arm 32 carrying the contact point 33. This arm 32 is urged toward the right as by a spring 34, so as to tend to bring the contact 33 into engagement with the stationary contact 35. If the temperature is sufficiently low, the spring 34 causes the contacts 33 and 35 to close and the electromagnet 55 25 is energized.

50 The source of electrical energy for the circuit is shown in this instance as provided by a thermopile structure 36 adapted to be influenced by the main burner flame. Accordingly no current flows in the circuit of electromagnet 25, since the burner is inactive. The complete circuit for the electromagnet 25 may be traced from thermopile 36, arm 32, contacts 33 and 35, coil of electromagnet 25, clock control switch 37, back to the thermopile 36. The clock control switch 37 55 may be arranged as to cause deenergization of electromagnets after a predetermined period of activity of the oven, irrespective of the position of the circuit controller 33-35.

70 The control circuit for electromagnet 15 includes the contact points 38 and 39. Contact point 38 is carried on a movable arm 40, and contact point 39 is stationary. In the position shown these contacts 38 and 39 are open, where- 75 by it is assured that the electromagnet 15 is

deenergized. The source of electrical energy for this control circuit is a pilot generator or thermopile 41. This pilot generator is subjected to the flame 42 of the pilot burner 43. This pilot burner is connected as by conduit 44 to the inlet chamber 5 of the valve structure 3. Accordingly should the pilot flame 42 be extinguished for any reason, the electromagnet 15 will be deenergized and the valve structure will be caused to assume the inactive position of Fig. 1. Thus the flow of fuel to main burner 1 is stopped.

The complete circuit for the electromagnet 15 may be traced as follows: from pilot generator 41, arm 40, contacts 38 and 39, the coil of electromagnet 15, clock control switch 37, back to the pilot generator 41.

In order that the valve be rendered active so as to place the thermal responsive control of electromagnet 25 into operation, the contacts 38 and 39 must be closed and the pilot 43 must be lit. Also, the clock control switch 37 must be in closed position. With all of these three conditions present, the valve first passes to the low fire position of Fig. 2. The high fire position is not attained, because the thermopile generator 36 is not active, and the control circuit for electromagnet 25 is unenergized. However, as soon as a low fire position is reached, the flame of burner 1 soon causes the generator 36 to be active, and the circuit for electromagnet 25 is energized. The valve then can pass to the high fire position of Fig. 3 if contacts 33, 35 are closed and this continues until the temperature attained is sufficient to separate contacts 33 and 35. Thereafter the closing and opening of the contacts 33 and 35, under the control of the temperature responsive pressure cell 31, is accomplished as required by the temperature obtaining in the oven.

Upon the elapsing of a predetermined time, the clock control switch 37 is opened and the system is shut down, as represented in Fig. 1.

Control of the closing and opening of the contacts 38 and 39 is shown in this instance as accomplished by manual rotation of a shaft 55. This shaft has a manually controlled handwheel 45 by the aid of which it may be rotated. Shaft 55 carries a cam 46 having a high point adapted to cooperate with the arm 44. When the high point 47 is in the position of Fig. 1, the arm 40 is urged toward the left, and the contacts 39 and 38 are opened. Just as soon as shaft 44 is rotated in a clockwise direction, the contacts 38 and 39 are permitted to close, and the valve structure 3 is thus permitted to be placed under the independent control of the temperature responsive device 31.

Rotation of the shaft 55 also serves to adjust the temperature of response of circuit controller 33-35. For this purpose the shaft 55 is provided with another cam 48. This cam 48 operates upon the right hand end projection 49 of the bellows 30. The position of the right hand end of the bellows 30 as determined by cam 48 obviously adjusts the degree of expansion required of bellows 30 to open the contacts 33, 35. Accordingly the cam 48, in adjusting the position of the left hand end of the bellows 30, simultaneously adjusts the temperature at which the vapor pressure is sufficient to expand the bellows 30, to open the contacts 33 and 35. Cam 48 has a high point 50, corresponding to inactive position, in which the contacts 33 and 35 must remain open irrespective of the temperature attained by pressure cell 31. As shaft 55 is turned

in a clockwise direction to close contacts 38 and 39, the temperature at which contacts 33 and 35 open is increased, since the right hand end of the bellows 30 is permitted to move toward the right, under the influence of spring 34.

The setting of the temperature at which the contacts 33 and 35 will open is thus determined by the angular position of the cam 48. Accordingly it is possible to indicate the average temperature to be attained in the oven by the aid of the dial 51 fastened to the shaft 55. This dial 51 may carry appropriate scale marks 52 adapted to cooperate with a stationary index point.

A limiting stop 53 may be provided for counter-clockwise rotation of shaft 55, and to ensure that the cam 46 will not pass beyond the position illustrated in Fig. 1.

By appropriate rotation of the dial 51, therefore, from the inactive position of Fig. 1, two main effects are attained. One is the immediate engagement of contacts 38 and 39. This renders the valve structure 3 responsive to the control provided by contacts 33 and 35. The other main effect is the adjustment, by continued rotation of shaft 44 through a required angle, of the temperature at which contacts 33 and 35 will open. This is accomplished by the cooperation of the cam 48 with the bellows 30.

The dominant control is lodged in the clock control switch 37. When this switch opens both of the electromagnets 15 and 25 are deenergized and the valve closes. While the clock control switch 37 is closed, the dominant control of valve 3 is effected by contacts 38 and 39. However, in the event of pilot flame failure this control is nullified and the valve structure 3 is closed.

Assuming that the pilot burner 43 is not extinguished, and that contacts 38 and 39 are closed by a rotation of shaft 44, then by alternate opening and closing of contacts 33 and 35, the valve structure 3 assumes alternately the low fire and high fire positions. This opening and closing of these contacts is dependent upon the temperature control provided by the pressure cell 31.

What is claimed is:

1. In a temperature controlled fuel burner system, means for causing the burner to assume only a high fire or a low fire condition, means responsive to temperature for controlling the burner optionally to assume either the high fire or the low fire condition, and a common means for adjusting the temperature at which the temperature responsive means operates, and for causing the burner to assume an active condition.

2. In a temperature controlled fuel burner system, means for causing the burner to assume only a high fire or a low fire condition, means responsive to temperature for controlling the burner optionally to assume either the high fire or the low fire condition, means for adjusting the temperature at which the temperature responsive means operates, means for causing the burner to assume an inactive condition, and means cooperating with the temperature adjusting means and the means for causing the burner to assume an inactive condition, to ensure that the burner remains in inactive condition when the temperature is adjusted to a limiting value.

3. In a temperature controlled fuel burner system having a valve structure adapted to be

electrically controlled to cause the valve to close, or to cause the burner to burn with high fire, or to cause the burner to burn with low fire, a circuit controller adapted to control the valve to cause it to be placed either in high fire or low fire position, a circuit controller adapted to cause the valve to be placed in inactive or active position, means responsive to attainment of low and high temperature limits for operating the circuit controller respectively for high fire or low fire valve position, and for operating the circuit controller to cause the valve to be placed in active position.

4. In a temperature controlled fuel burner system having a valve structure adapted to be electrically controlled to cause the valve to close, or to cause the burner to burn with high fire, or to cause the burner to burn with low fire, a circuit controller adapted to control the valve to cause it to be placed either in high fire or low fire position, a circuit controller adapted to cause the valve to be placed in active or inactive position, temperature responsive means for operating the circuit controller for high fire or low fire valve position, a pair of rotary members respectively for adjusting the temperature response of the first circuit controller, and for operating the second circuit controller, and a common operator for both said rotary members.

5. In a temperature controlled fuel burner system having a valve structure adapted to be electrically controlled to cause the valve to close, or to cause the burner to burn with high fire, or to cause the burner to burn with low fire, a circuit controller adapted to control the valve to cause it to be placed either in high fire or low fire position, a circuit controller adapted to cause the valve to be placed in inactive or active position, temperature responsive means for operating the circuit controller for high fire or low fire valve position, and thermopiles operated by consumption of fuel by the burner for supplying energy controlled by said circuit controllers.

6. In a temperature controlled fuel burner system having a valve structure adapted to be electrically controlled to cause the valve to close, or to cause the burner to burn with high fire, or to cause the burner to burn with low fire, a circuit controller adapted to control the valve to cause it to be placed either in high fire or low fire position, a circuit controller adapted to cause the valve to be placed in inactive or active position, temperature responsive means for operating the circuit controller for high fire or low fire valve position, a common means independent of temperature, for adjusting the temperature of response of the circuit controller for high or low fire valve position, and for operating the circuit controller to cause the valve to be placed in active position, thermopiles operated by consumption of fuel by the burner for supplying energy controlled by said circuit controllers.

7. In a temperature controlled fuel burner system having a valve structure adapted to be electrically controlled to cause the valve to close, or to cause the burner to burn with high fire, or to cause the burner to burn with low fire, a circuit

controller adapted to control the valve to cause it to be placed either in high fire or low fire position, a circuit controller adapted to cause the valve to be placed in inactive or active position, means responsive to attainment of low and high temperature limits for operating the circuit controller respectively for high fire or low fire valve position, and adjusting means cooperating with both said circuit controllers, for causing the temperature responsive controller to become active and for setting the valve structure so that it may respond to said temperature responsive control.

8. In a temperature controlled fuel burner system having a valve structure with a closure member adapted to assume a valve closing position, a low fire position and a high fire position, electrical control means which when unenergized causes the closure to remain at all times in closing position, separate electrical control means for causing the closure to assume either a high-fire or a low-fire position in accordance with the energization or deenergization of said separate control means, means responsive to attainment of low and high temperature limits for energizing or deenergizing said separate control means, and means independent of temperature, for energizing or deenergizing the control means that when unenergized, causes the closure to assume closing position.

9. In a temperature controlled fuel burner system having a valve structure with a closure member adapted to assume a valve closing position, a low-fire position and a high fire position, electrical control means which when unenergized causes the closure to remain at all times in closing position, separate electrical control means for causing the closure to assume either a high-fire or a low-fire position in accordance with the energization or deenergization of said separate control means, temperature responsive means for energizing or deenergizing said separate control means, means independent of temperature, for energizing or deenergizing the control means that when unenergized causes the closure to assume closing position, and a common means for optionally rendering both of said control means active or inactive.

10. In a temperature controlled fuel burner system having a valve structure with a closure member adapted to assume a valve closing position, a low fire position and a high fire position, electrical control means which when unenergized causes the closure to remain at all times in closing position, separate electrical control means for causing the closure to assume either a high-fire or a low-fire position in accordance with the energization or deenergization of said separate control means, temperature responsive means for energizing or deenergizing said separate control means, means independent of temperature, for energizing or deenergizing the control means that when unenergized causes the closure to assume closing position, means for adjusting the temperature of response of the temperature responsive means, and means whereby the control means for causing the closure to remain in closing position, is rendered effective when the adjusting means is adjusted below a limiting temperature.

WILLIAM A. RAY,
